UNITED STATES PATENT OFFICE.

TOBIAS BÄUERLE, OF ST. GEORGEN, GERMANY.

CLOCK WITH STRIKING TRAINS FOR HOURS AND QUARTERS.

Application filed November 22, 1920. Serial No. 425,933.

To all whom it may concern:

Be it known that I, TOBIAS BÄUERLE, a citizen of the German Republic, residing at St. Georgen, Germany, have invented certain new and useful Improvements in Clocks with Striking Trains for Hours and Quarters, of which the following is a specification.

Clocks of known construction with striking trains for hours and quarters comprise separate devices for releasing or for operating the striking trains for the hours and the striking trains for the quarters, such clocks comprise further either separate drives or they are coupled with the drive of the clockwork by means of a change speed gear, differential reversing gear or epicyclic gear. Such clockworks are therefore comparatively complicated and they present further the inconvenience that a rather large driving power is required for starting the striking train, this starting being accompanied by much noise.

Whilst, owing to the separate releasing devices for the two striking trains, separate step discs for each striking train were required, it has become possible through the present invention to operate both trains from one shaft so that only one step disc is required. From the essential simplification of the whole clockwork there results a very easy and noiseless working. According to the invention the disc for striking the hours is connected with the disc for striking the quarters mounted upon the same shaft by means of a differential gear which is also mounted on this shaft so that when one striking disc is locked the other striking disc is driven by the common shaft and vice versa. The alternating locking or stopping of the striking discs is effected through an angle lever which by means of another lever mounted upon the same axle is controlled by the pin disc for the quarters which is mounted directly upon the minute shaft.

The adjustment and the releasing of the number of strokes for the hours and quarters is effected in the well known manner from the minute- or hour-shaft by means of steps and driver with the accessory parts.

In the accompanying drawings the invention is shown by way of example in connection with a Westminster clockwork.

Fig. 1 is a front elevation.

Fig. 2 is a plan view of the improved clockwork.

Fig. 3 is a front elevation, the front plate being removed.

Fig. 4 shows the differential gear.

Fig. 5 represents in a diagrammatic view the escapement for the striking train.

Fig. 6 shows a modified construction of the differential gear.

The improved clockwork comprises two separate driving shafts 1, 2 with rope drums 3, 4, the first of which is designed for operating the clockwork, the second one being designed for operating the striking train. At the side of the drum 4 a toothed wheel 5 is loosely mounted which is connected in the well known manner through a spring influenced pawl 6 with the counter ratchet wheel 7 of the drum 4. The toothed wheel 5 operates through the intermediary of a wheel 8 the shaft 9 which carries the differential gear. A wheel 10 mounted upon the same axle 9 is connected with the pin wheel 14 through axle 11, wheel 12 and axle 13, said pin wheel being connected with the fly- ing pinion 15.

Upon the shaft 9 the striking disc 17 for the hours is loosely mounted which is fast with the wheel 16. This wheel 16 meshes with the wheel 18 which is mounted in a lever 19 rigidly connected with the shaft 9. A wheel 19 mounted upon the same axle as wheel 18 engages with the inner teeth of a toothed crown 20 loosely mounted upon the shaft 9, said toothed wheel 20 serving as a striking disc for the quarters and being connected through the wheels 21, 22 with the musical cylinder 23 which in the well known manner operates through its pins 24 the hammer levers 25. The striking disc 17 for the hours acts in the well known manner by means of the lever 26 upon the arm 27 for striking the hours which in the form of construction shown by way of example lifts simultaneously four hammers 25 for striking.

A smooth rimmed disc 29 with notches 28 is connected with the striking disc 20 for the quarters. The nose of a lever 30 slides upon the smooth rim of said disc 29, said lever 30 being keyed, together with the lever 31, upon a common axle 50, said lever 31 reaching with its bevelled end into the path of the striking disc 17 and locking said disc as long as the lever 30 slides upon the rim of the disc 29. As soon as the nose of the

lever 30 drops into the notch of the disc 29, whereby said disc is stopped, the lever 31 releases the striking disc 17. This angle lever 30, 31 therefore serves for alternately stopping the striking disc 17 for the hours and the disc 29 and through said disc the striking disc for the quarters. The levers 30 and 31 are controlled through a lever 32 which is keyed upon the same axle as the angle lever 30, 31 (Figs. 1 and 5) and adapted to be operated in the well known manner through a pin-disc 34 mounted upon the minute shaft 33, said pin-disc 34 having three short pins 35 and a long pin 36. Only the long pin 36 serves for lifting the lever 32 whereby the nose of the lever 30 is withdrawn from the notch of the disc 29 so that said disc is released, the striking disc for the hours being simultaneously stopped through the disc 31. Upon the hollow shaft for the hours the stepped disc 37 is mounted which presents the steps for the hours and the intermediary smaller steps for the quarter, the half hour and three-quarter hour, said intermediary steps being arranged on a lower plane than the hour steps. This stepped disc serves for limiting the descent of the lever 38 influenced by the spring 54 and of the curb 39 rigidly connected with said lever 38.

The release and the movement of the curb is effected in the well known manner from shaft 11 through the intermediary of the detent 40, ratchet 41 and snail 42. The detent 40 is lifted through its lever arm 43 from the studs 35, 36 of the quarter disc 34.

The depth of the different quarter steps and hour steps of the step disc 37 is calculated so that, when the lever 39 drops upon one of said steps, the curb 39 is moved for a number of teeth which corresponds with the number of the quarter hours and hours to be struck. For striking half an hour for example the curb descends for two teeth, and it drops for 12 teeth for striking eight o'clock. Within one hour the work has to strike ten quarter strokes upon which follow the hour strokes, that is to say after every tenth quarter stroke the disc 29 with the quarter disc 30 has to be stopped, whereby the hour disc 17 is released whilst, before the first quarter stroke of each hour, the stopping of the quarter disc has to be interrupted the hour disc having to be stopped.

55 This is effected in the following manner:— After the hour has been struck, the disc 29 remains still stopped through the nose of the lever 30. Shortly before the first quarter stroke the long pin 36 of the quarter disc lifts the lever arm 43 of the detent 40 and through this detent the snail 42 whereby the curb 39 is released so that the lever 38 drops upon the first quarter step, the curb being rotated for the length of one tooth. At the same time the long pin 36 lifts also the lever

32 whereby the lever 30 is made to release the disc 29, the hour disc being simultaneously locked through the second lever 31. The work is now ready for the first quarter stroke. This is struck after the pin 36 has passed under the lever arm 43 of the detent whereupon this lever arm descends and the detent releases in the well known manner the gear through the catch 44. The lever 32 remains raised so that the quarter-striking disc can revolve. At the following strokes for the half hour, for the three-quarter hour and for the four strokes for the full hour the same operation takes place with the exception that the lever 32 is not lifted any more by the three shorter pins 35, this being no longer necessary as after the first quarter stroke the nose of the lever 30 can slide upon the smooth rim of the disc 29. After the four strokes before the hour have been struck, that is to say after the tenth quarter stroke, the disc 29 has completed one revolution and the nose of the lever 30 drops into the notch 28 of the disc 29 as the lever 32 is not raised through the fourth pin (a short pin) the disc 29 being thus stopped and the hour disc being released through lever 31 so that the hour strokes can be struck.

The play begins again after the hour has been completely struck. As the striking train requires more driving power than the clockwork, a wheel 48 loosely mounted at the side of the rope drum 3 and coupled through a differential gear 45 with a driving shaft 1 of the clockwork 46 is brought in engagement with the loose wheel 5 of the striking train by means of a wheel 47. This has been done for the purpose to be able to use equal weights for the two rope drums 3, 4, the weight for the striking train being lighter and the weight for the clockwork being heavier than necessary. In this manner there is obtained that when the striking train begins to operate, part of the driving power of the clockwork is transferred to the driving shaft for the striking train.

The driving for the clockwork and the striking train can be effected in any convenient manner.

The invention can of course be used for any other clockwork with striking train for hours and quarters.

Fig. 6 shows a differential change gear 120 for the alternate operation of the striking train for the hours or for the quarters in which, instead of the wheels 16, 18, 49 and the studs of the toothed crown, bevel wheels 51, 52, 53 are used. The operation is exactly the same as hereinbefore described.

I claim:—

1. An improved clockwork with striking trains for hours and quarters comprising in combination with the usual clockwork an 130

hour disc and a quarter disc mounted upon one and the same shaft and a differential change gear between said hour disc and quarter disc and the driving shaft of the 5 clockwork for operating and alternately locking said discs.

2. An improved clockwork with striking trains for hours and quarters comprising in combination with the usual clockwork an 10 hour disc and a quarter disc mounted upon one and the said shaft, two levers rigidly connected with an axle, a third lever for

controlling said levers rigidly connected with said axle, a pin disc for the quarters mounted upon the minute shaft of the clockwork 15 for alternately stopping the said two striking discs.

In testimony whereof I affix my signature in presence of two witnesses.

TOBIAS BÄUERLE.
